UNITED STATES PATENT OFFICE.

ISAIAH B. ROBBINS, OF STOCKTON, CALIFORNIA, ASSIGNOR OF ONE-HALF
TO JOSEPH S. MORGAN, OF BROOKLYN, NEW YORK.

DUMPING-CAR.

SPECIFICATION forming part of Letters Patent No. 255,888, dated April 4, 1882.

Application filed May 25, 1881. (No model.)

To all whom it may concern:

Be it known that I, ISAIAH B. ROBBINS, a citizen of the United States, residing at Stockton, in the county of San Joaquin and State 5 of California, have invented certain new and useful Improvements in Dumping-Cars and Methods of Unloading Same by Means of Compressed Air; and I do hereby declare the following to be a full, clear, and exact description of the invention, such as will enable others skilled in the art to which it appertains to make and use the same, reference being had to the accompanying drawings, and to letters or figures of reference marked thereon, which 10 form a part of this specification.

My invention relates to certain improvements in dumping-cars such as are used in constructing and ballasting railroads, excavating and filling, for transporting coal, gravel, and 15 ores, and in the application thereto of power by means of compressed atmospheric air, so that in the immediate and direct process of unloading or dumping manual labor may be wholly dispensed with. I attain the above 20 very desirable objects by the mechanism illustrated in the accompanying drawings, in which—

Figure 1 is an end view of a car platform and frame, showing air-cylinders and air-pipe attachment, the platform-sections being in the 25 position of discharging. Fig. 2 is a bottom view of car platform and frame, showing their connection with air-cylinders and air-pipe. Fig. 3 is a detached side view of one side of 30 the car-frame, showing one of the adjustable side boards attached to its standards. No part of a running-gear is shown in the above views, as I base no claim thereupon, my improvements being solely in the car-body and application thereto, for unloading, of power by means 35 of compressed atmospheric air.

Similar letters refer to similar parts throughout the several views.

I construct the car-body as follows: The 40 platform is made in two longitudinal sections, A A. The frame is composed of sides C C and ends B B, and is strengthened by transverse timbers F, located near each of the ends B. These timbers F have an opening at their 45 centers and serve as points of connection for air-cylinders, as will be hereinafter shown. Each

platform-section A, at its outside edge, is hinged to its respective frame side C, so as to admit of each section being independently tilted for the purpose of discharging its load, 55 or both simultaneously.

Standards D are attached, as shown, one to each end of the frame sides C, and are provided with slots. Side boards, E, are loosely bolted into the slots of standards D, so as to 60 permit of the free escape of the load when platform-sections A are tilted.

Power to unload is applied by means of compressed atmospheric air in the following manner: Air-cylinders G are provided each with a 65 piston having an oval head, a, secured, as shown, beneath and at the central opening of each of the transverse timbers F to permit the necessary up and down movements of the heads a through said openings. The two cylinders G are connected beneath by an air-pipe, H, which has in each end a stop-cock, e. The air-pipe H of each car is connected to that of the immediate front or rear car by any suitable coupling. The stop-cocks e can be shut off 70 or turned on, as required, so as to shut off or permit the flow of air and thus permit unloading of one single car of a train or of any 75 number of cars simultaneously, the line of air-pipes H being of course connected to and supplied with compressed air from any desired 80 style of air-compressing apparatus.

When the pressure is applied for the purpose of unloading the car or cars the pistons with oval heads a, responding to said pressure, 85 lift the inner longitudinal edges of the platform-sections A, which, being hinged, as shown, to frame sides C, are readily tilted and relieved of their loads, the side boards, E, yielding to the pressure of the load and permitting its free 90 discharge.

Although it is not absolutely essential to use the side boards, E E, yet I claim there is a decided advantage in their use—viz., that the load may be placed nearer the outer edges of 95 the platform and away from its direct center, thus requiring less labor in loading and less lifting-pressure of air to unload. I also prefer that the inner longitudinal edges of the sections A A be provided with stationary side 100 boards to properly divide the load and prevent its falling upon the piston-heads, &c.

Having thus fully described my invention, what I claim, and desire to secure by Letters Patent, is—

1. In combination with the platform-sections A A, hinged to the frame sides C C, the cylinders G G, the piston-rods of which are provided with oval heads a, attached beneath and at the circular openings of the transverse timbers F F of the car-frame and connected together by an air-pipe, H, having a stop-cock, c, in each end, the said air-pipe H being connected to that of the other cars, and the entire series being connected with and supplied with compressed air from any style of air-compressing apparatus, all substantially as herein described and set forth.
2. In a dumping-car, the platform constructed in two longitudinal sections, each section hinged to its respective frame side, in combination with air-cylinders attached beneath the said platform-sections to transverse timbers of the car-frame, the pistons of said cylinders having oval heads and moving upward to tilt the platform-sections in response to pressure of compressed air forced through pipe connecting the cylinders, said pipe having stop-cocks in each end adapted to shut off or admit the supply of air so as to unload one car only or several simultaneously, as herein shown and described.
3. In a dumping-car, the combination of a platform made in two center-opening longitudinal sections and tilting right and left, the air-cylinders, and devices tilting the platform-sections by pressure of compressed atmospheric air, substantially as described.
4. In a dumping-car, a platform composed of longitudinal sections A, hinged to the frame sides C, said frame sides C having bolted thereto standards D, provided with slots carrying side boards, E, which latter are loosely bolted in the slots of standards D, so as to permit of the free escape of the load when the platform-sections A are tilted for that purpose, all as herein shown and described.
5. In a dumping-car, as a means of unloading the same, the combination of a platform made in two longitudinal sections which are hinged each to its respective side of the car-frame, air-cylinders attached beneath transverse timbers of car-frame, provided with pistons having oval heads working upward through openings in said transverse timbers, and an air-pipe connecting the air-cylinders together and having a stop-cock in each end, which air-pipe, being connected to any suitable compressed-air apparatus, permits by a proper adjustment of the stop-cocks a flow of compressed air into the cylinders, the pistons of which, responding to the pressure, permit the oval heads to raise the platform-sections and discharge their loads to right and left, substantially as herein described.
6. In combination with a railroad or similar car, a platform made in two longitudinal sections, A, hinged each to its respective sides C of the car-frame, and having applied thereto power by means of compressed atmospheric air supplied from any air-compressing apparatus through air-pipe H to air-cylinders G, attached to and beneath transverse timbers F of car-frame, as and for the purposes specified.
7. The air-cylinders G G, attached beneath the transverse timbers F F, arranged in relation to platform-sections A A and air-pipe H, the latter being provided with stop-cocks c c and connected with any air-compressing apparatus, so that air may be forced through said pipe H and air-cylinders C C to raise platform-sections A A by its pressure, all substantially as and for the purposes herein set forth.

In testimony whereof I have affixed my signature in presence of two witnesses.

ISAIAH B. ROBBINS.
